DESIGN FOR A BOTTLE

William Frank Nichols, Philadelphia, Pa., assignor, by mesne assignments, to Continental Distilling Corporation, Philadelphia, Pa., a corporation of Delaware

Application May 21, 1935, Serial No. 56,937

Term of patent 14 years

To all whom it may concern:

Be it known that I, William Frank Nichols, a citizen of the United States, residing at Philadelphia, in the county of Philadelphia and State of Pennsylvania, have invented a new, original, and ornamental Design for Bottles, of which the following is a specification, reference being had to the accompanying drawing, forming part thereof.

In the drawing:

Fig. I is a front view of a bottle showing my new design.

Fig. II is an edge view of the bottle.

Fig. III is a back view of the bottle; and

Fig. IV is a cross section taken as indicated by the arrows IV—IV in Fig. II.

I claim:

The ornamental design for a bottle, as shown and described.

WILLIAM FRANK NICHOLS.
